UNITED STATES PATENT OFFICE.

ALFRED BERTHON, OF PARIS, FRANCE.

TELEPHONE-TRANSMITTER.

SPECIFICATION forming part of Letters Patent No. 319,548, dated June 9, 1885.

Application filed November 14, 1884. (No model.) Patented in France March 22, 1884, No. 161,121, and in England March 4, 1885, No. 2,893.

To all whom it may concern:

Be it known that I, ALFRED BERTHON, of Paris, in the Republic of France, have invented a new and useful Improvement in Telephone-Transmitters, which improvement is fully set forth in the following specification.

This invention relates to telephone-transmitters which are used in connection with a battery, and operate to vary the resistance of the battery-circuit, and has more particular reference to that class of battery-transmitters in which granular particles of conducting material, and specially of carbon, constitute the variable-resistance medium, they being confined in a loose state between a vibratory diaphragm and a back plate, both of conducting material, and electrically connecting the diaphragm and back plate with each other. The poles of the battery-circuit are connected one with the diaphragm, the other with the back plate.

Heretofore in such transmitters the diaphragm and back plate have been made of metal, and the conducting particles have been retained by the walls of the instrument, so that they cover a large part of the surface of the plate. Heretofore, also, rounded particles or shot of conducting material have been placed in a tube of non-conducting material at the center of the diaphragm and confined between it, or a button carried by it, and a back plate. In one case the tube has been of soft rubber, and attached both to the diaphragm and back plate, in another, of wood, and fastened only to the back plate.

The present invention comprises certain novel constructions and combinations, as follows:

First. A vibratory carbon plate, supported at the edges, constitutes the diaphragm, and the back plate is also made of carbon, the loose particles of conducting material being confined between and in contact with said plates in any ordinary or suitable way. The advantage of the carbon plates in this connection is that a better contact is made, (probably on account of the surface structure of the carbon plate, and if carbon particles are used, as they usually would be, on account also of the like nature,) while at the same time vibrations are better transmitted than in the case of a carbon

button attached to the diaphragm. A carbon diaphragm is not new in itself, but is new in the combination stated.

Second. The carbon back plate as well as the carbon diaphragm is supported at the edges so that it is capable of vibrations. It is not new to employ two vibratory plates supported at the edges in a battery-transmitter; but in all heretofore known the plates have been, so far as I am aware, of metal.

Third. The space behind the back-plate is left open either by omitting the back of the case or, better, by perforating it with one or more holes. The latter construction is better because it gives more protection to the back plate.

Fourth. The loose particles of conducting material are held in a rigid cup of insulating material, supported upon the carbon back plate, and keeping the particles together in the center of the carbon diaphragm with which it makes contact. This is found to give better articulation than when the carbon particles extend to the edges of the diaphragm, probably because the variable-resistance medium is acted upon only by that part of the diaphragm having the largest vibration. It also has the effect of increasing the resistance of the transmitter and diminishing the weight of the mass of particles, and also of lessening the tendency of the particles to pack.

Fifth. The conducting particles are made of small carbon grains, about one millimeter in diameter, more or less, and of irregular shape. Balls of carbon of two millimeters and over in diameter would not give the same result. They could, of course, be used in connection with the carbon back plate and carbon diaphragm, but not advantageously. The small particles of irregular form are advantageous, because they give the same number of contacts with less weight, and because the irregularity in form gives contacts better suited to telephonic transmission. The combination of such particles with a diaphragm, when they are loosely confined at the center of the diaphragm by a cup, is believed, broadly, to be new, whether the contact be directly with the diaphragm or with a button carried thereby.

Sixth. In order to leave the conducting particles perfectly free to move among themselves,

the rigid cup is not filled full, but is only partly filled, so that when the instrument lies on its back there is no electrical connection with the diaphragm. In order to make the instrument operative, it is turned more or less on edge, so that the particles will fall down against the diaphragm. This construction is believed to be new, broadly, whether the diaphragm or a button attached thereto makes contact with the particles, and irrespective of the material of which said diaphragm or button is made.

Seventh. A flaring or funnel-shaped cup is used to retain the conducting particles in the center of the diaphragm. This is advantageous, because it allows the particles to fall down more readily against the diaphragm without giving too great an inclination to the instrument. It is preferred to adjust it so that the diaphragm and back plate are inclined forty-five degrees, the inclination of the sides of the funnel-shaped cup making about the same angle with the axis of the funnel.

Eighth. The foregoing elements are combined with one another, the combination constituting an improved transmitting-instrument with sundry advantages. Having now explained the principle of the invention, what is considered the best mode of applying the same will be described, with the aid of the accompanying drawings, which make a part of this specification.

Figure 1 is a front view, partly in section, of a telephone-station apparatus provided with a transmitter constructed in accordance with the invention; Fig. 2, a cross-section of the same; Fig. 3, a diagram illustrating the arrangement of circuits; Fig. 4, a view, half plan and half section, of the transmitter on an enlarged scale, and Fig. 5 a cross-section of the transmitter.

A is the box or case of insulating material—hard rubber, for example; B, the carbon back plate; C, the carbon diaphragm; D, the flaring or funnel-shaped cup, of rigid insulating material, (hard rubber,) and E the mass of loose carbon particles constituting the variable-resistance medium.

Both plates B C are or may be made in any suitable way of artificial carbon—that is, of the same composition as that of which the carbons for electric-arc lamps are made. Practically a cylinder is pressed out through a die, as in making lead pipe. The cylinder is slit and spread out, and a circular disk is cut by a sharp-edge die. The plates are then baked in a furnace. Their thickness is preferably from one and one half to two millimeters, (1½ to 2 mm.) They are or may be used in the condition in which they leave the furnace. The mass E is composed of grains or small particles of retort or gas carbon, obtained of equal size by careful sifting. Grains of one millimeter or less in diameter are suitable. The weight of the mass E is only a few centigrammes.

The back plate is supported at the edges by the soft-rubber ring F, which also separates it from the back of the box or case A. The diaphragm or vibratory front plate, C, is supported at its edges by the ring G, of soft rubber, which separates it from the back plate, B. The ring G is or may be three to three and one-half millimeters (3 to 3½ mm.) in thickness. The plates are confined by the screw-ring H, 70 75 of brass or other material. A soft-rubber ring, I, is interposed between the ring H and the diaphragm C. The object of using soft-rubber rings is to act as cushions to prevent the carbon of the plates from being crushed in screwing up the ring H. They also hinder the production of abnormal vibrations in the use of the instruments.

No mouth-piece is used, although one could be employed. Its use is not desirable, except 85 upon long lines, because while it increases the loudness of the speech transmitted it renders the sounds more strident.

The exterior conductors are connected with the diaphragm and back plate by means of 90 binding-posts permanently in electrical connection, one with each carbon plate, by a wire, 100 and 101, respectively, say, of silver, whose ends are flattened, one end being confined between the carbon plate and the adjacent rubber ring, and the other clamped between the back of the case and the base of the binding-post.

The flaring or funnel-shaped cup D is fastened at the smaller end to the back plate, B, by 100 gum-arabic, gum-lac, or other adhesive material. The cup has no bottom, so that the carbon particles rest upon the back plate. It is filled, preferably, about five-sixths (5/6) full, although the exact amount is not essential. It 105 could be filled so high that the particles make contact with the diaphragm when the instrument is horizontal, with the diaphragm uppermost; but it is better to leave a space at the top, so that the particles are left freer to move among themselves, and make contact with the diaphragm only when the instrument is turned more or less on its edge.

The height of cup D is less than the thickness of ring H, so that it does not touch the 115 diaphragm C. The latter may, therefore, vibrate freely.

In use the transmitter is tipped at an angle—say, forty-five degrees. As shown, it is supported at the end of the arm K. In 120 the bottom of the box A are a number of holes or perforations, Q. The instrument will operate without them; but when used they make the transmission stronger.

The arrangements of the station apparatus 125 may be those in ordinary use, the improved transmitter being substituted for that in use. As shown, some slight modifications are introduced. The transmitter is included in the circuit 1 with a battery of, say, one or two 130 cells Leclanché and the primary wire of an induction-coil, L. The secondary wire of the

induction-coil (being, say, one hundred and fifty ohms resistance) is included in a branch, 2, of the main line, which branch includes also the hand-telephones M. The spring-key N, 5 when the latter is on its back contact, is included in the branch 3 with the signal-bell. (Not shown.) The back contact is, at the end of branch 4, connected with the battery.

When the line is not in use, the hand-telephones hang on the hooks on each side of the apparatus. The hook on the right forms part of the ordinary automatic gravity-switch. Normally, the signal-bell only is in circuit. To signal central office or another station on 15 the same line, the key N is pushed in, thus including the battery in the line, and cutting out the bell at the signaling station.

When the telephone is removed from the switch-hook, the bell and key are cut out, the 20 main line is completed through branch 2, and the battery-circuit 1 is established through the transmitter.

When one talks before the transmitter, the carbon diaphragm C is thrown into vibrations, 25 which are communicated to the mass E of carbon particles and also to the carbon back plate. The result is a variation in the resistance of the battery-circuit 1, producing corresponding undulations in said circuit and 30 through the action of the induction-coil in the main line.

The transmission of the voice is exceedingly strong and clear, without irregularity of any 35 nature, no matter whether the words are spoken in a high or in a low tone, and whether near the diaphragm or at a distance of some centimeters. Ten centimeters' distance is the most suitable. It is not necessary, after a certain time, to shake this transmitter, in order to renew the contact-surfaces of the grains, but, if 40 shaken, it continues to transmit equally well.

Although I have given a detailed description of one of the improved transmitters, I do not intend to limit myself to these details, 45 as they can be varied without departing from the spirit of the invention. Parts also of the invention can be used separately.

The transmitter could of course be used in the same circuit with a battery and telephone receiver, instead of being connected 50 therewith through an induction-coil, although this would not be a desirable arrangement considering the low resistance of the transmitter.

Having now fully described my said invention and the manner of carrying the same into effect, what I claim is—

1. In a telephonic transmitter, the combination, with a vibratory carbon plate supported 60 at the edges and a carbon back plate, of interposed carbon particles loosely confined in contact with said plates, substantially as described.

2. The two carbon plates, both supported at the edges, so as to be capable of vibrating, 65 in combination with the interposed particles of conducting material, such as carbon, loosely confined in contact with said plates, substantially as described.

3. The combination, with the vibratory carbon plate supported at the edges and the loose particles of conducting material, of the carbon back plate supporting the cup of non-conducting material, whereby the loose particles of conducting material are held in contact with the aforesaid vibratory plate, substantially as described. 70 75

4. The two vibratory plates of carbon supported at the edges, in combination with an interposed medium of high resistance for completing the circuit between said plates, so as to allow the resistance of such circuit to be varied in accordance with the vibrations of 80 said plates, substantially as described.

5. In a telephone-transmitter, and in combination with the vibratory diaphragm and the conducting particles, the cup of non-conducting material for containing said particles, the same being flaring or funnel-shaped, substantially as described. 85 90

6. The combination, with the vibratory front plate and the back plate, both inclined to the horizontal, of the flaring or funnel-shaped cup of non-conducting material and the loosely 95 confined particles of conducting material, substantially as described.

7. In a telephone-transmitter, the combination, with the diaphragm and back plate, of a rigid cup attached to the back plate and separated from the diaphragm, and the mass 100 of loose conducting particles partly filling said cup, so that when the instrument is horizontal no circuit is established through the instrument, but when the latter is raised the particles fall forward and complete the circuit, substantially as described. 105

8. In a telephone-transmitter, the combination, with the diaphragm, of a rigid cup and the small irregular carbon particles loosely 110 confined in said cup at the center of the diaphragm, the said particles constituting the variable-resistance medium, substantially as described.

9. The combination of the case having the back open or perforated, the two vibratory 115 plates supported at the edges in said case, and the variable-resistance medium between said plates, substantially as described.

In testimony whereof I have signed this specification in presence of two subscribing 120 witnesses.

A. BERTHON.
